United States Patent Office.

ROLAND H. SMITH, OF PITTSBURG, PENNSYLVANIA,

Design No. 3,065, dated June 2, 1868.

DESIGN FOR A STREET-LAMP POST.

The Schedule referred to in these Letters Patent and making part of the same.

TO ALL WHOM IT MAY CONCERN:

Be it known that I, ROLAND H. SMITH, of the city of Pittsburgh, and county of Allegheny, and State of Pennsylvania, have originated and designed a new Pattern for a Street-Lamp Post, of which the following is a full, clear, lucid, and exact description, reference being had to the accompanying drawing, making part of this specification.

In the accompanying drawing—

Figure 1 is an elevation of my design for a lamp-post, (drawn to one-eighth full size.)

My design for a street-lamp post consists in providing the base with a semicircular bottom, A, on top of which is a round ring, B, above which is a series of leaf-like scrolls in relief, as seen at C, with their points facing upward. The outside form of these scrolls is an ogee. There are four of these leaf-like scrolls in this part, facing north, south, east, and west.

The part above C represents a cable or cylindrical iron band, D, passing around spirally at an angle of about ten degrees. There are eighteen of these spiral rings in all above.

D is another series of leaf-like scrolls in relief, with an outside line of an ogee, E, the point of them facing downward. There are four of these scrolls in all, one north, south, east, and west.

At the top of E are two cylindrical rings, F F. Above F F is a series of leaf-like scrolls in relief, the points of which face upward, G, the outside line of which is an ogee. There are four of these scrolls, one facing north, one south, one east, one west.

On the top of G are represented twelve elongated round-ended leaves, as at H, with their points facing upward, above which is a fluted tapered Corinthian column, I, with twelve concave grooves or flutes, J, running upward.

At the top of J is a series of leaf-like scrolls in relief, K, of an outside line of an ogee, four in number, one facing north, one south, one east, and one west, their points facing downward, above which is a ring of grape-berries, as seen at L, passing around and dividing the scrolls K from a series of leaf-like scrolls in relief, M, of an ogee-form on the outside, with their points facing upward. There are four of these scrolls, one facing north, one south, one east, and one west.

The design now enlarges into another ogee, as seen at N, with a series of round-ended leaves, eight in number, in relief O, with their points facing upward. These leaves O form the apex or top of the post.

At P P are two brackets coming down from the top of the post, and joining the grape-berries, as at L. These brackets are of ogee-form, and represent a bent branch with leaves sprouting out in relief at different places. These brackets are for the ladder to rest upon when the lamp is being lighted.

The form of my design, independent of the irregularities of the scrolls in relief, is cylindrical.

My design is applicable for either wooden or cast-metal lamp-posts.

Having, then, described the nature of my design, what I claim as my invention and design, and desire to secure by Letters Patent, is—

The design or pattern for lamp-posts herein set forth and shown.

ROLAND H. SMITH.
